Fig. 3

Fig. 4

Fig. 5

FIG. 1 is a perspective view of a tire embodying our new design, it being understood that the full line portion is repeated throughout the circumference of the tire, shown by means of broken lines;

FIG. 2 is an enlarged fragmentary plan view of the full line portion shown in FIG. 1;

FIG. 3 is a fragmentary sectional view taken substantially on the plane indicated by the line III—III in FIG. 2; and

FIGS. 4 and 5 are fragmentary sectional views, respectively, taken substantially on the planes indicated by the lines IV—IV and V—V in FIG. 3.

The dominant features of our design reside in those portions shown in full lines in the drawings.

We claim:

The ornamental design for a tire, substantially as shown and described.
